UNITED STATES PATENT OFFICE.

JOHN CAMERON AND BOYCE RANDOLPH, OF DETROIT, MICHIGAN.

BIN.

No. 509,148.

Specification of Letters Patent.

Patented Jan. 12, 1906.

Application filed December 30, 1897. Serial No. 208,628.

To all whom it may concern:

Be it known that we, JOHN CAMERON and BOYCE RANDOLPH, citizens of the United States of America, residing at Detroit, in the county of Wayne and State of Michigan, have invented certain new and useful Improvements in Bins, of which the following is a specification, reference being had thereto to the accompanying drawings.

10 The invention relates to the construction of bins, more particularly designed for use in stores beneath the counter, and the invention consists in certain features of construction as hereinafter set forth.

15 In the drawings, Figure 1 is a vertical cross section through the bin; Fig. 2 is an elevation of a store counter illustrating a series of bins arranged therebeneath.

20 It is one of the objects of the invention to utilize all of the available space beneath the counter, and at the same time to facilitate the withdrawal of material from the bin and the filling of the bins when empty.

25 It is a further object to provide means for displaying to the customer the material with which the bin is filled without exposing the same to injury.

To accomplish these objects, the bin A is preferably formed of a size to fit beneath the counter and extending substantially from front to rear thereof. It is preferably of rectangular form and may be constructed of any suitable material, but preferably of sheet metal. For filling the bin, an 30 opening B is formed in the rear wall, near the upper end, which may be closed by a hinged lid C, preferably so arranged that when drawn out it forms a hopper for directing the material into the bin. The lower portion of the bin is formed of a hopper shape by inclined plates D and E. The plate E extends from the rear wall forward, and is preferably of an arch-shape, so as to provide greater strength for supporting the 35 weight of the material. This plate terminates a short distance from the bottom F of the bin, leaving an opening G, through which the material may flow outward into the compartment H beneath the plate E. 40 This compartment H also forms a receptacle for holding the scoops or other devices employed for withdrawing the material.

45 I is a door, or lid, for covering an opening at the bottom of the rear side of the bin 50 into the compartment H. This door is pivotally attached to the bin, the pivots being

so located that when the door is opened it will swing upward and inward, as indicated in dotted lines, thereby avoiding any rearward projection to interfere with the passageway behind the counter. The forward plate D is inclined, as shown, so as to direct the material within the bin rearward towards the discharge opening G.

55 For displaying the contents of the bin, a detachable tray J is provided, which fits behind an opening K at the top and front of the bin, and preferably in an inclined portion L of the front wall. This tray J is preferably formed of sheet metal having 60 grooved flanges on three sides thereof for receiving a glass plate M. The material to be displayed is placed in the tray between the transparent plate and the metal back, and the tray is then held in position preferably by engaging its lower flange with hooks or bent flanges N on the bin, and its upper end with a spring hook O. Thus, the tray may be readily removed and replaced by inserting the hand through the 65 opening B and engaging or disengaging the tray from the hook O.

70 With a construction as described, the series of bins may be placed beneath a counter, as illustrated in Fig. 2, and filled with various materials. A sample of the contents of each bin is then placed in the detached tray J, and the latter then inserted, as described, so that the sample will be displayed through the transparent plate and the opening K at 75 the front of the bin. As fast as the material is withdrawn from the compartment H, it will be replaced by the material above the partition I, this operation continuing until the whole supply is exhausted. The bin 80 may then be refilled by opening the lid C, as has been described.

85 What we claim as our invention is:

1. The combination with a counter, of a bin therebeneath extending from front to rear thereof, having fill and delivery openings in its rear side respectively at top and bottom thereof, a hinged door or lid for said fill opening forming a hopper for directing the material therein, a display tray detachably secured within said bin in registration with an aperture in the front side thereof, an inclined partition within the bin for directing the material thereabove forward, and having a rearwardly opening discharge between its lower end and the bottom of the bin, and an oppositely inclined partition for

directing the material rearwardly towards said discharge opening.

2. The combination with a counter, of a bin therebeneath extending from front to rear thereof, fill and discharge openings at top and bottom respectively at its rear side, an arched partition within said bin forming an incline for directing the material towards the front of the bin, and having a rearwardly opening discharge between its lower edge and the bottom of the bin, an oppositely inclined partition for directing the material rearwardly, and a door or lid for closing the lower opening in said rear wall adapted when opened to be entirely within the space beneath the hopper, and when closed to be in a direct vertical line with the rear wall of the bin.

3. The combination with a counter, of a bin therebeneath extending from front to rear thereof, and having fill and delivery openings respectively at the top and bottom of its rear side, lids or doors for closing said openings, and a display tray insertible through the fill opening and detachably secured within said bin in registration with an aperture in the front side thereof.

4. The combination with a counter, of a bin therebeneath extending from front to

rear thereof, having fill and delivery openings in its rear side respectively at top and bottom thereof, a hinged door or lid for said fill opening forming a hopper for directing the material therein, an inclined partition within the bin for directing the material thereabove forward, and having a rearwardly opening discharge between its lower end and the bottom of the bin, and an oppositely inclined partition for directing the material rearwardly towards said discharge opening.

5. A bin formed of sheet metal having fill and discharge openings at top and bottom respectively at its rear side, an arched partition within said bin forming an incline for directing the material towards the front of the bin and having a rearwardly opening discharge between its lower edge and the bottom of the bin, and an oppositely inclined partition for directing the material rearward towards said discharge opening.

In testimony whereof we affix our signatures in presence of two witnesses.

JOHN CAMERON.
BOYCE RANDOLPH.
